UNITED STATES PATENT OFFICE.

LAMBERT C. KOOPMANS, OF CHICAGO, ILLINOIS, ASSIGNOR TO E. PAYSON SMITH,
OF SPRINGFIELD, ILLINOIS.

RETAINING VALVE ANCHOR.

Application filed September 9, 1927. Serial No. 218,434.

My invention relates to means whereby the retaining valves of the air lines may be properly anchored or secured to the end walls of railroad cars, while at the same time permitting any necessary adjustment, as well as removal and replacement of the retaining valve or of the air line to be made from the car exterior. That is to say, my invention has for its object the provision of means whereby the retaining valve may be firmly secured to the wall of the car and permit attachment and detachment of the valve without entering the car and therefore without necessitating removal of the lading in the car.

The objects and advantages of my invention will be readily comprehended from the detailed description of the drawings, wherein:

20 Figure 1 is a front elevation of my improved valve anchor with a retaining valve secured thereto and to the end of an air pipe which is broken away.

Figure 2 is a side elevation thereof.

25 Figure 3 is a perspective view of the anchoring means.

Figure 4 is a side elevation of anchor and retaining valve, illustrating a modification of my invention.

30 Figure 5 is a perspective view of the modified form of anchoring means shown in Figure 4.

Figure 6 is a front elevation of retaining valve shown secured to a modified form of anchoring means.

35 Figure 7 is a side elevation of the construction shown in Figure 6.

Figure 8 is a perspective view of the anchoring means employed in Figures 6 and 7.

40 The invention, as exemplified in the first three figures, comprises a plate having a car wall engaging portion 10 and a valve attaching or holding portion 11, both of which preferably extend parallel with each other. These portions 10 and 11, especially when the anchoring means is intended to be employed on a car having an end wall of boards arranged flush with each other, are preferably arranged in different vertical planes so that the valve holding portion 11 may be in spaced relation with the adjacent portion of the car wall which is indicated by the vertical line 12. That is to say, the construction shown in these figures consists

gular, bent or off-set intermediate of the upper and lower ends as shown at 13.

The car wall engaging portion 10 at suitably spaced points is provided with bolt or rivet holes 14, 14 to receive the bolts or rivets whereby the anchor is attached to the car wall, namely adjacent to the top and at the upper end of the air pipe 15 to which the air retaining valve 16 is secured.

The retaining valve 16, which is of a well known construction, is usually provided with laterally disposed lobes or ears 17, 17 which are apertured to receive the securing rivets or bolts. With my improved anchor, the valve holding bolts are not secured to the car wall; but these bolts, shown at 18, 18, pass through the apertures in the lobes 17, 17 and through an apertured longitudinal bar 19, disposed horizontally rearward of the attaching portion 11 of the anchor.

The attaching portion 11 of the anchor is of transverse width somewhat less than the distance between the holes in the oppositely disposed lobes or ears 17, 17, as shown in Figure 1; and the bar 19 is of length sufficient to permit the apertures in its ends to register with the respective holes in the lobes or ears. The bending or off-setting of anchor portion 11 is sufficient to permit a plate of ample strength and thickness to be easily inserted between the car wall (indicated at 12) and the anchor plate 11.

The anchor portion 11 need merely be of a width sufficient to provide ample strength and a proper bearing surface for plate 19 whereby sidewise tilting of the retaining valve is prevented. That is to say, the width of portion 11 may be such that sidewise adjustment of the retaining valve relative to the anchor may be made before either bolt 18 engages with the side of anchor portion 11.

After the bolts 18, 18 have been inserted in the registering holes in plate 19 and the valve lobes 17, 17, the threaded ends of the bolts are provided with nuts as shown at 20, whereby the plate 19 and lobes 17, 17 are drawn toward each other and therefore into firm clamping relation with the attaching portion 11 of the anchor.

As the portion 11 is of substantial length, it is clearly apparent that vertical adjustment of the valve 16 relative to the anchor may be easily made; and that the comparatively large contacting surface between the

portion 11 and bar or plate 19 will prevent relative movement between the elements when the nuts 20 on bolts 18 have been firmly screwed into place.

5 The construction of anchor shown in Figure 3 is preferably employed with the attaching portion 11 disposed upwardly from the car attaching portion 10. If for any reason it becomes necessary to reverse the 10 position of the anchor, the clamping means shown will firmly hold the valve in place. However, where the anchor is to be attached in this inverted or reverse manner, I prefer to employ the structure disclosed in Figures 15 4 and 5, where the anchor is substantially similar to the previously described construction and consists of the car attaching end or portion 21, having rivet or bolt receiving apertures 22, 22, and the valve attaching portion 23; the portions 21 and 23, like portions 10, 11, being off-set from each other in order to provide a pocket or spacing intermediate of portion 23 and the adjacent car wall, which is indicated at 12. Where the 25 anchor is to be disposed as shown in Figure 4, I prefer to have the lower end of portion 23 provided with a rearwardly disposed lip or flange 24, preferably of transverse width substantially equal to the width of the off-set 13, in order to permit the lip or flange 24 to abut against the wall of the car. It is apparent that with this construction, the valve clamping or holding means in the event it should become loosened cannot slip off the 30 anchor portion 23; the bent or off-set 13 and the lip or flange 24 providing a pocket closed at its upper and lower ends.

Instead of employing the plate 19 shown in Figure 2 for securing the retaining valve in place, a U-bolt 25 may be employed, of length sufficient to straddle the anchor portion 23 and to permit its threaded ends to pass through the apertures in the valve lobes 17, 17. The ends of the U-bolt are each threaded to a sufficient length to receive a nut 26 and permit the latter to be screwed thereon sufficiently to cause the U-bolt to come into snug relation with anchor portion 23 as shown in Figure 4.

50 In Figures 6 to 8, I illustrate another modification of my improved anchoring means, consisting of a flat plate 27 of sufficient thickness to provide the necessary strength and shown preferably rectangular.

55 The plate on one of its flat faces and preferably adjacent to one end is enlarged or increased in thickness which, for the sake of lightness and to save material, is preferably in the nature of the bosses 28, 28, shown reenforced by the connecting rib 29. The plate and bosses are provided with apertures 30, to receive the rivets or bolts whereby the plate is secured to the car wall; the enlargement or bosses being disposed toward the car wall as shown in Figure 7 to

maintain the main portion of the plate in spaced relation with the car wall. The spacing or pocket thus provided between the plate and car wall is sufficient to receive either a plate like plate 19 in Figure 2 or 70 a U-bolt 25; the ends of the U-bolt, like in Figure 4, passing through the apertured lobes or ears 17, 17 of the retaining valve 16. It will be understood that the width of the plate 27 is less than the distance between the apertures in the oppositely disposed lobes 17, 17 of the valve 16, so as to permit the holes in clamping plate 19 or the ends of U-bolt 25, to register with the holes in the ears 17, 17. 75 80

It is apparent, that with all of the constructions shown adjustments of the valve relative to the car wall, either vertically or laterally, may be readily made to compensate for any variations that may occur or 85 be found necessary in making replacements, by simply loosening the nuts 20 or nuts 26 without necessitating removal of the rivets or bolts whereby the anchoring means are attached to the car wall; unscrewing nuts 90 20 or 26 will permit the plate 19 or the U-bolt to slide on the anchor.

The various embodiments of the invention shown are believed to be the simplest and best forms, which have been described in 95 terms employed merely as terms of description and not as terms of limitation, as modifications may be made without, however, departing from the spirit of the invention.

What I claim is:—

1. A retaining valve anchor comprising a vertically arranged plate, the rear face of one end whereof is in a different vertical plane from the other end and constitutes a car wall engaging portion while the other end is held spaced from the car wall, and valve holding means involving a member disposed transversely of the rear face of said spaced end in adjustable relation therewith and elements for fastening the retaining valves to said member and to induce a clamping relation between said member and said last mentioned spaced end. 100 105 110 115 120

2. A retaining valve anchor comprising a plate, a portion whereof extends into a plane beyond that of the other portion for engagement with a car wall while the other portion is of less width and is held in spaced relation with the car wall, said last portion adjacent its free end being disposed rearwardly, 115 and means secured at the ends to the opposite sides of the valve and arranged in straddling relation with said second mentioned portion above said rearwardly disposed end, whereby the valve is adjustably secured to the anchor. 120 125

3. A retaining valve anchor comprising a plate apertured at one end to permit attachment to a car wall, said end having a vertical face disposed into a plane beyond the vertical 130

plane of the non-apertured portion of the plate, and means, disposed transversely of the rear face and about the sides of said non-apertured portion, whereby the retaining valve is adjustably clamped to the anchor.

4. A retaining valve anchor comprising an elongated member, one end whereof is apertured and constitutes the car wall engaging end while the other non-apertured end constitutes the valve holding end, the rear face of the first mentioned end being arranged in a vertical plane removed from the rear face of the other end of the plate, and a clamping member disposed transversely about said non-apertured end and operatively connected with the retaining valve, whereby the latter is adjustably clamped in place.

5. A retaining valve anchor comprising an elongated member, a car wall engaging portion arranged at one end of the member whereby the latter is spaced from the car wall, and retaining valve holding means disposed transversely about the rear face of said member whereby the valve is clamped to the said member.

6. A retaining valve anchor comprising a plate provided with a rearwardly projecting enlargement at one end for spacing the plate from the car wall, said end being apertured to receive means for attaching the plate to the car wall, and retaining valve holding means adapted to extend about the rear face and sides of the plate for adjustably clamping the valve to said plate.

LAMBERT C. KOOPMANS.
